(57) **CLAIM**

The ornamental design for a pet feeder, as shown and described.

DESCRIPTION

FIG. 1 is a front view of a pet feeder showing my new design;

FIG. 2 is a rear view thereof;

FIG. 3 is a top view thereof;

FIG. 4 is a bottom view thereof;

FIG. 5 is a left-side view thereof, with the right-side view being a mirror image thereof;

FIG. 6 is a front, top and right-side perspective view thereof; and,

FIG. 7 is a front, bottom and left-side perspective view thereof.

The broken lines shown (i.e. letters and a contour thereof) represent unclaimed subject matter of the pet feeder and form no part of the claimed design. The thin lines shown represent ridgelines of three-dimensional shape of the pet feeder.
